UNITED STATES PATENT OFFICE.

GEORGE T. FIELDING, OF NEW YORK, N. Y.

ADVERTISING MEDIUM.

1,082,311.

Specification of Letters Patent. Patented Dec. 23, 1913.

Application filed June 5, 1913. Serial No. 771,865.

To all whom it may concern:

Be it known that I, GEORGE T. FIELDING, a citizen of the United States, and a resident of the city of New York, borough of the Bronx, in the county and State of New York, have invented a new and Improved Advertising Medium, of which the following is a full, clear, and exact description.

The object of the invention is to provide a new and improved advertising medium more especially designed for use in show windows and the like, and arranged to effectively advertise a desired line of merchandise by attracting the attention of passersby for a considerable length of time.

In order to accomplish the desired result use is made of a casing in which is mounted an intermittently traveling web provided with a series of advertising panels, which preferably pertain to the nature of the article to be advertised, the traveling web moving the panels successively into a display opening formed in the face of the casing, and an intermittently moving slide controlling the said opening to open the same at the time the web is at a standstill, and to close the opening during the time the web is moving.

A practical embodiment of the invention is represented in the accompanying drawings forming a part of this specification, in which similar characters of reference indicate corresponding parts in all the views.

Figure 1 is a front elevation of the advertising medium; Fig. 2 is a rear elevation of the same with the casing in section; Fig. 3 is a sectional plan view of the same on the line 3—3 of Fig. 2; Fig. 4 is an enlarged perspective view of portions of the slide and web and the means for imparting movement thereto; Fig. 5 is a rear face view of part of the slide and its connection with the actuating medium; and Fig. 6 is an enlarged sectional rear face view of the actuating means for the web and slide.

The advertising medium is mounted in a suitably constructed casing A provided with an opaque front B preferably covered by a glass pane b. The front B preferably terminates at its upper edge a distance below the top of the casing and the lower edge

of the front B is a distance above the bottom of the casing (see Fig. 1) so as to leave the upper and lower portions of the glass pane b unobstructed for advertising matter pertaining to the subject matter to be advertised. The outer face of the front B is provided with a picture depicting matter relative to the subject matter to be advertised, as shown, for instance, matter pertaining to smoking and smoker's articles.

In the opaque front B is arranged a display opening B' adapted to be periodically opened and periodically closed by an intermittently moving slide C, and in the display opening B' are adapted to appear successively advertising panels D' arranged on an endless web D having an intermittently traveling motion in the direction of the arrows indicated in Fig. 3. The movement given to the slide C and the web D is such that the slide C moves into an open position relatively to the display opening B' during the time the web D is at a standstill, and the slide moves into a closed position relative to the display opening and keeps the latter closed during the time the web D is traveling to move the next following panel D' into register with the display opening B'. The panels D' of the web D are of a diaphanous material and the interior of the casing A is illuminated by electric lamps E and E' so that the panels D' in register with the display opening B' are clearly visible during the night to attract the attention of passersby.

Each of the panels D' contains advertising matter pertaining to the subject to be advertised; for instance, as shown in the drawings, several of the panels D' are provided with representations of smokers in different attitudes, and also with panels having legends pertaining to the matter to be advertised. The front face of the slide C is provided with an attractive picture C' pertaining to the matter to be advertised; for instance, as shown in the drawings, the opening B' and the slide C form a portion of a panel of a package of tobacco depicted on the front B. Thus when the slide C is in an open position the corresponding registering panel D' appears to form part

of the package of tobacco. The top and bottom portions of the glass pane *b* not covered by the front *B* are provided with legends pertaining to the subject to be advertised, the legends being illuminated during the night from the rays of light emanating from the lamps *E* and *E'*.

In order to impart the desired motion to the slide *C* and the traveling web *D*, the following arrangement is made: The upper end of the slide *C* is provided with a sleeve *C*² mounted to slide on a guide rod *C*³ attached to the casing *A*, and the lower portion of the slide *C* is guided on a guide rod *C*⁴. The back of the slide *C* is pivotally connected by a link *C*⁵ with the upper end of a lever *F* pivoted at *F'* on a bracket *A'* attached to the casing, and the lower end of the lever *F* is pivotally connected by a link *F*² with the upper end of a lever *G* fulcrumed on a stud *H* held on a gear casing *H'* mounted on a base *H*² of insulating material held on the bottom of the main casing *A*. The lower end of the lever *G* is provided with a fork *G'*, the members of which are adapted to be engaged by a crank pin or a friction roller *I'* held on a crank arm *I* secured on a shaft *I*² journaled in the gear casing *H'* and driven by a gearing *J* mounted in the said gear casing *H'*. The gearing *J* is driven by a motor *K*, preferably of the electric type mounted on the base *H*² and connected with a source of electrical energy, the same as the electric lamps *E* and *E'*. On the base *H*² is mounted a rheostat *L* and a converter *N* in the circuit for the electric motor *K*, to permit connecting the electric motor with a direct or alternating current.

When the motor is running the crank pin *I'* imparts an intermittent swinging motion to the lever *G* so that the slide *C* is moved from an open position into a closed position and held therein for the time being, after which the slide is moved into an open position and held therein for the time being. The web *D* passes around vertically-disposed rollers *D*² and *D*³ journaled in the casing *A*. The web *D* is provided with a binding *D*⁴ provided with spaced eyelets *D*⁵ adapted to be engaged by a lug *O'* projecting transversely from the free end of an arm *O* fulcrumed at *O*² on a carrier *P* mounted to reciprocate on a guide rod *P*² attached to the casing *A* in the rear of the guideway *C*³ previously mentioned. The arm *O* is pressed on by a spring *O*³ attached to the carrier *P* so as to engage the lug *O'* with an eyelet *D*⁵ for imparting a traveling motion to the web *D* in the direction of the arrows *a'*. The lug *O'* is provided with a projection *O*⁴ to limit the inward movement of the lug *O'* into an eyelet *D*⁵ and the lug *O'* is rounded off on the opposite side of the

projection *O*⁴ so that the lug readily passes out of the eyelet during the return movement of the carrier *P*. The eyelets *D*⁵ are spaced apart a distance corresponding to the width of a panel *D'* so that at each movement of the carrier *P* in one direction the web is shifted to move the next following panel *D'* into register with the display opening *B'*. During the return movement of the carrier *P* the lug *O'* on account of being rounded off slips out of the eyelet *D*⁵ and travels over the rear face of the binding *D*⁴ without imparting movement to the web.

In order to safeguard the web against return movement use is made of a spring pawl *Q* (see Fig. 2) attached to the casing and bearing with its beveled end on the upper head of the roller *D*², to prevent return movement of the latter and consequently return movement of the web *D*.

The carrier *P* is pivotally connected by a link *P*² with the upper end of a lever *R*, similar to the lever *F* and fulcrumed at *R'* on the bracket *A'*. The lower end of the lever *R* is pivotally connected by a link *R*² with the upper end of a lever *S* fulcrumed on the stud *H*, and provided at its lower end with a fork *S'* similar to the fork *G'* of the lever *G*. The members of the fork *S'* are engaged by a crank pin or friction roller *I*³ on the crank *I* and spaced from the crank pin or friction roller *I'*, as plainly indicated in Fig. 6 so that the crank pin or friction roller *I*³ imparts a swinging motion to the lever *S* at the time the lever *G* is at a standstill. It will be noted that the crank pins *I'* and *I*³ are practically at a right angle to each other so that the above-described movement is given to the levers *G* and *S* to cause the slide *C* and the web *D* to travel at the proper time, so that when the slide *C* is in an open position a panel is displayed in the opening *B'*, and when the slide *C* is in a closed position and at rest relative to the display opening *B'* then a traveling movement is given to the web *D* to move the next following panel *D'* into register with the display opening *B'*. The bearings *T* for the roller *D*² are fixed on the brackets *A'* and *A*² forming part of the casing *A*, while the bearings *T*² for the roller *D*² are adjustably mounted on the said brackets by the use of set screws *T*² so as to permit of giving the desired tension to the web *D*. When the motor *K* is running the slide *C* is moved from a closed position relative to the display opening *B'* into an open position, and remains therein for a short time, so that one of the panels *D'* in register with the display opening *B'* is visible to the passersby. The slide *C* next moves into closed position relative to the display opening *B'* and remains in this closed position during the time the

web D is shifted to move the following panel D' into register with the display opening B'. The slide C next moves into open position, as previously mentioned, and during 5 this time the carrier P is on the return stroke with the arm O traveling over the binding D⁴ from one eyelet D⁵ to the next following one, it being understood that at the time the lug O' drops into the next following eyelet D⁵ the slide C has returned 10 to closed position so that the web can now be moved without being seen by the spectators.

It will be noticed that by the arrangement 15 described different advertising panels appear successively in the display opening B' and consequently the attention of passersby is attracted for a considerable length of time, as the passersby watch the appearance and 20 disappearance of the panels in the regular order.

Having thus described my invention, I claim as new and desire to secure by Letters Patent:

1. An advertising medium, comprising a support having a display opening, an intermittently traveling web provided with a series of advertising matter adapted to successively register with the said display opening, an intermittently moving slide controlling the said display opening, a rotating crank provided with spaced crank pins, levers alternately and intermittently actuated by the said crank pins, and connections between the said levers and the said web and slide to move the slide into open position relative to the said display opening while the web is at a standstill, and to move the slide into a closed position relative to the display opening and to keep the latter closed during the time the web is moving.

2. An advertising medium, comprising a support having a display opening, an intermittently traveling web provided with a series of advertising matter adapted to successively register with the said display opening, an intermittently moving slide controlling the said display opening, a motor driven crank provided with spaced crank pins, levers having forks alternately and intermittently actuated by the said crank pins, a lever and link connection connecting one of the forked levers with the said slide, a carrier mounted to slide and provided with an arm engaging the said web to move the latter in one direction only, and a lever and link connection connecting the other forked lever with the said carrier.

3. An advertising medium, comprising a casing having a front provided with a display opening, rollers journaled in the casing and arranged on opposite sides of the said display opening, an endless web pass-

ing around the said rollers and provided with advertising panels adapted to register 65 successively with the said display opening, the web having spaced eyelets along one edge, a spring-pressed arm having a lug at its free end adapted to engage the said eyelets, a carrier mounted to slide in the direction of the length of the web and on which carrier the said arm is pivoted, and means for imparting an intermittently reciprocating motion to the said carrier to move the web in one direction. 75

4. An advertising medium, comprising a casing having a front provided with a display opening, rollers journaled in the casing and arranged on opposite sides of the said display opening, an endless web passing 80 around the said rollers and provided with advertising panels adapted to register successively with the said display opening, the web having spaced eyelets along one edge, a spring-pressed arm having a lug at 85 its free end adapted to engage the said eyelets, a carrier mounted to slide in the direction of the length of the web and on which carrier the said arm is pivoted, a crank arm, means for turning the said crank arm, a lever having a fork adapted to be engaged by the said crank arm for imparting an intermittent swinging motion to the said lever, and a connection between the said lever and the said carrier. 95

5. An advertising medium, comprising a casing having a front provided with a display opening, rollers journaled in the casing and arranged on opposite sides of the said display opening, an endless web passing 100 around the said rollers and provided with advertising panels adapted to register successively with the said display opening, the web having spaced eyelets along one edge, a spring-pressed arm having a lug at its 105 free end and adapted to engage the said eyelets, a carrier mounted to slide in the direction of the length of the web and on which carrier the said arm is pivoted, means for imparting an intermittent reciprocating motion to the said carrier to move the web in one direction, and means for holding the web against movement in the opposite direction. 110

6. An advertising medium, comprising a 115 casing having a front provided with a display opening, rollers journaled in the casing and arranged on opposite sides of the said display opening, an endless web passing around the rollers and provided with 120 advertising panels adapted to register successively with the said display opening, the web having spaced eyelets along one edge, a spring-pressed arm having a lug at its free end adapted to engage the said eyelets, a 125 carrier mounted to slide in the direction of

the length of the web and on which carrier the said arm is pivoted, means for imparting an intermittent reciprocating motion to the said carrier to move the web in one direction, and a spring pawl held in the casing and engaging one of the rollers to hold the same against return movement.

In testimony whereof I have signed my name to this specification in the presence of two subscribing witnesses.

GEORGE T. FIELDING.
